DESCRIPTION

FIG. 1 is a right, front perspective view of a stabilizer jack showing my new design in extended position;

FIG. 2 is a top plan view thereof in an enlarged scale;

FIG. 3 is a bottom plan view thereof in an enlarged scale;

FIG. 4 is a front view thereof;

FIG. 5 is a rear view thereof;

FIG. 6 is a left side elevational view thereof; and,

FIG. 7 is a perspective view similar to FIG. 1 but showing the jack in a retracted position.
